LADY'S BLOUSE

Frank W. Netsky, Philadelphia, Pa., assignor to Susquehanna Waist Company, Philadelphia, Pa., a copartnership composed of Frank W. Netsky and Samuel Netsky

Application February 24, 1936, Serial No. 65,300

2 Claims. (Cl. 2—54)

This invention relates to ladies' blouses and generally like garments and more particularly to those made of somewhat rough and relatively thin material such as linen.

5 Blouses of this character tend to wear in the vicinity of the juncture of the sleeve and under side of the armhole more rapidly than at other points, a condition principally due to the constant rubbing of the under side of the sleeve against the 10 body of the garment adjacent the armhole and the rubbing of the wearer's skin against the inner face of the fabric when in use, especially if the garment is made of material such as linen which has a relatively hard but somewhat roughened 15 surface. Additionally, of course, the effect of perspiration and moisture on the material lying beneath the armpit is deleterious to the fabric and thus accelerates wear due to the abrasive action, if it may be so termed, induced by the rubbing of the adjacent plies of the fabric upon each 20 other and against the wearer's skin.

Various ways of preventing or at least minimizing this condition have been proposed but none of them, so far as I am aware, has been entirely 25 satisfactory. Thus, for example, the use of a covered rubber dress shield of the well known type is objectionable for in blouses of the character to which my invention relates it is unsightly when the garment is viewed from the inside and very 30 definitely shows through the fabric when the blouse is being worn, while if made of plain rubber without a covering the shield has a "feel" frequently objected to by women and if made of rubber enclosed in fabric it is bulky and sometimes 35 irritates the skin, and in either case must be removed prior to laundering the garment and replaced thereafter before it is re worn.

Furthermore, while a shield made of a textile material similar or approximately similar to that 40 of which the garment itself is made has heretofore been suggested, those of which I am aware have either included a seam overlying the seam joining the sleeve and body of the blouse under the armhole or when not including such a seam 45 have embodied excessive fullness at this point, in either case constricting the wearer's freedom of movement and causing considerable discomfort because of the presence of the added thickness of material in or adjacent the armpit.

50 A principal object of my invention, therefore, is to provide a lady's blouse or similar garment embodying novel means forming a permanent part thereof for minimizing wear of the fabric in the vicinity of the sleeve and under side of the arm- 55 hole yet of a character which does not detract

from the appearance of the blouse when it is being worn and which enhances its appearance when viewed from the inside; which provides a neat and attractive finish at the point of convergence of the various seams at the lower side of the armhole; which is effective to absorb perspiration or other moisture in the vicinity thereof; which does not materially enhance the cost of the garment; which has no unobjectionable feel to the wearer's skin and no tendency to irritate the latter however delicate; which does not appreciably add to the bulk of material beneath the armpit; which does not have to be removed or replaced when the blouse is laundered, and which in no way inconveniences the wearer or causes discomfort when the garment is being worn.

Other objects, advantages and novel features of design, construction and arrangement comprehended by the invention are hereinafter more particularly pointed out or will be apparent from the following description of one embodiment thereof as illustrated in the accompanying drawing in which

Fig. 1 is a fragmentary front view of the sleeve and adjacent portion of the body of a lady's blouse embodying the invention, with certain parts broken away for clearness of illustration.

Fig. 2 is a fragmentary enlarged plan view of the garment shown in Fig. 1 adjacent the junction of the seams beneath the armhole as it appears when the blouse is spread out flat and viewed from the inside; and

Figs. 3 and 4 are greatly enlarged sectional views on lines 3—3 and 4—4 respectively.

Throughout the drawing the same symbols are used to designate the same parts in the several figures.

More particularly, as shown, the blouse comprises a body portion 1 and a sleeve 2 of abbreviated type though of course the length of the sleeve is a matter of choice as long as it extends for a short distance outwardly from the armhole, it may be finished with a cuff 3 defined by suitable stitching. The body is cut out in the usual way to form the armhole and the inner end of the sleeve united to the marginal edge thereof by stitching 4. In like manner the front and back panels of the body are brought together at the sides and united by stitching 5, this seam merging into the seam 6 uniting the material of which sleeve 2 is formed at its under side. These several seams are preferably of the character known as "French seams" formed by spaced rows of stitches successively sewn from opposite sides of the material whereby the pres-

ence of raw edges is avoided. This construction of the body and sleeve of the blouse is therefore of the usual character and requires no further or more specific description.

5 In accordance with my invention I dispose an additional layer or ply of material at the point of convergence of the several seams to which reference has been made in such manner that it will extend outwardly therefrom in all directions adjacent the inner side of the material of which the sleeve and body are formed for a distance approximating that in which the maximum wear, induced by the aforesaid causes, takes place and thereby form a shield to protect 10 the blouse fabric from contact with the wearer's skin and also to give a sort of cushioning effect behind the fabric adjacent the armpit which, I have found, materially reduces the wear on the outer surfaces thereof resulting from the more 15 or less constant rubbing when the blouse is being worn. This shield I form of the same material as the body and sleeve of the garment or of some other suitable textile material, preferably one of substantially similar texture, as it then imparts the same "feel" to the wearer's 20 skin and so gives no appreciable sensation of its presence when the blouse is in use and does not show through or become silhouetted to any marked extent when the arm is raised. Moreover, as the shield covers the point of juncture of the several seams it materially enhances the 25 appearance of the blouse when the latter is observed from the inside since any bunching or the like of the various seams is totally concealed and 30 a neat and attractive finish presented at a place which, in ordinary blouses, is necessarily rather unsightly.

More particularly, I form this shield of two separate and substantially similar pieces of material 7 and 8 each approximately semi-elliptical in shape. Along its curvilinear edge each piece may be scalloped, as shown, or otherwise attractively finished and the two pieces are united to each other and to the rest of the blouse by 40 stitching 9 as best shown in Figs. 2 and 4, this seam substantially coinciding with portions of the seams 5 and 6 adjacent the point at which they merge at the lower edge of the armhole. The shield is then secured transversely to the 45 blouse by short rows of stitches 10, 11 respectively adjacent opposite edges of the shield where they overlie the seam 4. Thus the edges of the shield are slightly gathered as at 12, 13 by the stitches 10, 11 so as to take up the slight fullness 50 at this point and thereby shape the shield to substantial conformity with adjacent portions of the blouse. Thus considering the shield as of substantially elliptical form, it is apparent that it is firmly united to the blouse along its minor 55 axis and only at the extremities of its major axis and can thus accommodate itself to relative movement between material forming the sleeve and that forming the body when the blouse is in use, the shield normally lying within the latter closely 60 adjacent the inner side of the fabric and extending outwardly in all directions from the point where the several seams unite as best shown in Fig. 1 in which the blouse is illustrated substantially as it would appear when in use and 65 the wearer's arm is raised toward a generally horizontal position. When the arm is lowered so as to bring the under side of the sleeve adjacent the side of the body, the shield of course moves with the arm and body material so as to 70 extend downwardly in the sleeve and in the body 75

respectively adjacent the inner side of those parts of the fabric which tend to rub on each other as the arm is moved relatively to the body, and the absence of any seam in the shield proper along its major axis, except at its extremities where 5 the stitches 10, 11 hold the shield to the seam 4, insures a smooth folded edge overlying this more or less upstanding seam or edge to protect the wearer from any contact therewith without increasing the bulk of material lying in and beneath the armpit to an amount which would cause discomfort or give the sensation of a "tight" armpit. Under these conditions the shield, as above pointed out, forms a cushion between the wearer's arm and body and the material forming the arm and body of the blouse and tends to greatly minimize the effects of the rubbing action therebetween when the wearer moves her arm, while, of course, since the shield is of linen or other material generally similar to 20 that of the blouse, it interposes an absorbent layer between the skin and the blouse material proper which greatly minimizes the deleterious effects of perspiration and moisture thereon and so maintains the original strength of the fabric 25 for a much longer time than would otherwise be retained. In consequence, the tendency of the blouse to wear more rapidly adjacent the wearer's armpits than at other points is negated and its useful life as a whole correspondingly prolonged, while the presence of the shield materially enhances the appearance when viewed from the inside.

Moreover, since the shield is a permanent part of the garment and equally washable therewith, 35 the necessity for removing and replacing it each time the garment is laundered is avoided, with consequent saving of a material amount of time and annoyance on the part of the owner.

While I have herein described one embodiment 40 of the invention with considerable particularity, it will be understood that changes and modifications may be made in the details thereof within the scope of the appended claims.

Having thus described my invention, I claim 45 and desire to protect by Letters Patent of the United States:

1. In a garment of the class described comprising a body and a sleeve having respectively intersecting side and underarm seams and a 50 seam connecting the body and sleeve, a substantially elliptical shield consisting of an initially flat single layer of flexible fabric of substantially the same material as the garment, forming a permanent part thereof and lying within the 55 body and the sleeve, stitching coextensive and in substantial alignment with one of the axes of the shield and securing it to said side and underarm seams, and means interconnecting the extremities of the other axis of the shield to the seam 60 between the body and sleeve, said stitching and said means constituting the sole connection between the shield and the garment, said shield being entirely free between said stitching and its attached extremities and the free portions 65 having substantially the same flexibility as the material of the garment.

2. In a garment of the class described comprising a body and a sleeve having respectively intersecting side and underarm seams and a 70 seam connecting the body and sleeve, a substantially elliptical shield consisting of an initially flat single layer of flexible fabric of substantially the same material as the garment, forming a permanent part thereof and lying within the 75

body and the sleeve, stitching coextensive and in substantial alignment with one of the axes of the shield and securing it to said side and underarm seams, and means interconnecting the other axis of the shield to the seam between the body and sleeve at points spaced from the first axis, said stitching and said means constituting the sole

connection between the shield and the garment, said shield being entirely free between said stitching and said means and the free portions having substantially the same flexibility as the material of the garment.

5
